UNITED STATES PATENT OFFICE.

HERMAN E. S. CHAYES, OF NEW YORK, N. Y., ASSIGNOR TO CHAYES DENTAL INSTRUMENT CORPORATION, OF NEW YORK, N. Y., A CORPORATION OF DELAWARE.

ATTACHMENT FOR DENTAL BRIDGEWORK.

Application filed December 17, 1924. Serial No. 756,410.

This invention relates in general to improvements in removable dental bridge work, and in particular to the construction of a separable connection between the bridge and 5 its piers.

In my Patent No. 1,366,058 January 18, 1921, there is described a dental bridgework structure which includes the use of socket members set in the gap-facing sides of the 10 pier teeth and adapted to removably hold T-headed anchor members projecting from the opposite ends of the dental bridge member. In the present invention, which is in the 15 nature of an improvement upon the construction described in the patent, the same general construction is followed, the improvement consisting principally in the particular construction of a T-headed anchor members by means of which the snugness of fit of the 20 T-heads in the sockets can be varied or increased at will either to restrict or to facilitate the movement of the bridge member relative to the piers during the process of mastication, to facilitate or restrict the ease of 25 removal of the bridge from, or placement in, position between the piers, or to take up wear in the connecting parts.

In one form of the invention the lateral 30 margins of the head are bent inwardly toward the outer surface to provide inward facing grooves in which a replaceable bridging plate can be held, means being provided for bending an intermediate portion of the plate toward or from the body of the head 35 and adjacent end of the stem.

Other objects and features of the invention 40 will be referred to in the course of the following description.

In the accompanying drawings, 45 Figure 1 is a view of a form of T-head member;

Figure 2 is a plan view of a part of the head member shown in Figure 1;

Figure 3 is a perspective view of a socket 50 member for use with the illustrated form of head member;

Figure 4 is a side elevation of the head member;

Figure 5 is a view similar to Figure 4, illustrating a modification; and

Figure 6 is an end view of the subject-matter of Figure 5, showing the attachment in place in a socket, the socket wall being partly broken away.

In Figures 1 and 2 I have shown a pre-

ferred form of embodiment of the invention, which includes several novel features of construction.

The anchor comprises a T-shaped member the stem of which is adapted to be permanently embedded in a body of inlay metal mounted in an artificial tooth forming part of a dental bridge. The transverse relatively flat head is adapted to seat in a socket member 11 illustrated in Fig. 3, which has a slot 15 of a depth somewhat less than that of the socket member and corresponding to the depth of the stem 3, which, as can be seen in Fig. 6, does not extend wholly to the lower edge of the head. By this construction the lower portions of the head and slot provide an effective lock against movement of the bridge away from the pier tooth.

In order to provide for varying the snugness of the fit of the T head in the socket member 11, the transverse head of the T member is furnished with means for resiliently pressing against the walls of the socket. This is accomplished by forming the vertical edges of the head with overhanging flanges forming confronting grooves 16. In these grooves are received the lateral margins of a spring plate 21. This plate normally tends to buckle outwardly away from the head, and may be held in desired position by means of a screw 22 engaging a tapped hole 23 in the adjacent end of stem 3. The plate 21 presses against the socket wall when in position, with more or less frictional resistance against withdrawal from the socket, in accordance with requirements and adjustment. After a time the plate may lose its resilience, or capacity for adjustment, whereupon it may be replaced.

This structure has the advantage that the part of the head which is active in maintaining the head in the socket, and which may need frequent adjustment, is not an integral part of the head, and hence if broken or worn out it may be replaced without affecting the rest of the attachment. The point will be clear if we consider the Figure 2 form of device. There the adjustment is by causing relative movement between the arms of the U-wing. Repetition of such movement will cause crystallization of the metal, with breaking off of all or part of a wing. When this happens the whole attachment has to be replaced, which means dismounting the bridge, taking off the artificial teeth, drilling out the stem, fitting a new attachment in proper relation to the

adjacent socket member, soldering, &c. With the Figure 1 form of device, there is no destructive reaction, resulting from adjustment, upon any part of the stem or head, except only 5 the replaceable plate 21. And when plate 21 needs to be replaced, this can be done very easily and quickly.

In Figures 5 and 6 the confronting grooves 16 are shown running transversely of the attachment head, so that when the socket and head are in their normal vertical position (Figure 1) the said grooves are horizontal. On account of this arrangement, no screw or other retaining means is necessary in order 15 to keep the spring plate 21 in place. Adjustment is easily made by regulating and coordinating two factors, the length of the spring plate and the extent to which it is bulged out (Figure 5) in order to make resilient contact 20 with the socket wall. With the attachment out of the socket it is easy to put in place or take out the spring plate. And when it is in the socket, of course, the plate cannot accidentally get out. This form of attachment 25 has many of the advantages of that shown in Figure 1, and it requires no independent fastening means.

The modification of Figs. 1 and 2 is disclosed in my application Serial No. 486,102, 30 filed July 20, 1921.

Inasmuch as many changes could be made in the above construction, and many apparently widely different embodiments of my invention could be made without departing 35 from the scope thereof, it is intended that all matter contained in the above description or shown in the accompanying drawings shall be interpreted as illustrative and not in a limiting sense.

It is also to be understood that the language 40 used in the following claims is intended to cover all the generic and specific features of the invention herein described and all statements of the scope of the invention which, as a matter of language, might be said to fall therebetween.

I claim:

1. In a head and slot connection for dental 50 bridgework, a solid stem having wings extending laterally from the end thereof in opposite directions and terminating in end portions bent towards each other and overlying the main wing portions but spaced from the same, and a spring plate having its edges held between the wings and the bent termini thereof and detachably connected to the stem.

2. A removable bridge comprising in combination a pier tooth with a denture receiving 60 socket, a bridge disposed adjacent the pier tooth, a shank integrally joined to the bridge and reaching to the socket, a head made on the shank and fitting into the socket, said head provided with confronting grooves, a separate spring plate having its edges confined 65 in the grooves and its intermediate portion

bulging outwardly beyond the plane of the grooved head and pressing against the socket wall.

3. The device set forth in claim 2, in which the confronting grooves are disposed transversely with respect to the head. 70

4. A removable bridge comprising in combination, a pier tooth provided with a denture receiving socket, a bridge disposed adjacent the pier tooth, a shank integrally joined to the bridge and reaching to the socket, a head made on the shank and fitting into the socket, said head provided with a groove, a separate spring plate flexibly mounted in the groove and pressing against the socket wall, 80 and means for retaining the plate in the groove.

5. A T-head attachment for the purpose set forth, having a separate wear plate removably carried on the outer face of the head. 85

6. A T-head attachment for the purpose set forth, having a separate wear plate removably carried on the outer face of the head and means for retaining the plate in position on the head. 90

7. removable bridge comprising in combination a pier tooth with a denture-receiving socket, a bridge disposed adjacent the pier tooth, a shank joined to the bridge and reaching to the socket, a head disposed on the end and transversely of the shank and fitting into the socket, and a separate wear plate removably carried on the outer face of the head and having surface engagement with the socket wall. 95

8. A removable bridge comprising in combination a pier tooth with a denture-receiving socket, a bridge disposed adjacent the pier tooth, a shank joined to the bridge and reaching to the socket, a head disposed on the end and transversely of the shank and fitting into the socket, a separate wear plate removably carried on the outer face of the head and pressing against the socket wall, and means for retaining the plate in position on the head. 105

9. A removable bridge comprising in combination a pier tooth with a denture-receiving socket, a bridge disposed adjacent the pier tooth, a shank joined to the bridge and reaching to the socket, a head disposed on the end and transversely of the shank and fitting into the socket, the outer side of the head being provided with confronting grooves, and a separate wear plate having opposite edges confined in the grooves and having surface engagement with the socket wall. 115

10. A removable bridge comprising in combination a pier tooth with a denture-receiving socket, a bridge disposed adjacent the pier tooth, a shank joined to the bridge and reaching to the socket, a head disposed on the end and transversely of the shank and fitting into the socket, the outer side of the head being provided with confronting grooves, a separate wear plate having opposite edges con- 125

130

fined in the grooves and having surface engagement with the socket wall, and means for retaining the plate in position on the head.

11. A removable bridge comprising in combination a pier tooth with a denture-receiving socket, a bridge disposed adjacent the pier tooth, a shank joined to the bridge and reaching to the socket, a head made on the shank and fitting into the socket, said head provided
- 5 with confronting grooves, a separate spring plate having opposite edges confined in the

grooves and having a portion projecting outwardly beyond the plane of the grooved head and making surface contact with the socket wall.

12. A T-head for the purpose described having a slideway formed in its outer surface and a separate wear plate received in said slideway.

In testimony whereof I affix my signature.

HERMAN E. S. CHAYES.
